John D. Marshbank, of Lancaster, Pa.
Letters Patent No. 893, Dated June 2, 1857.

The schedule referred to in these Letters Patent, and making part of the same.

To all whom it may concern:

Be it known that I, John D. Marshbank, of Lancaster City, County of Lancaster and State of Pennsylvania, have invented and designed the ornaments on a Cooking Stove; And I do hereby declare that the following is a full and exact description thereof, reference being had to the accompanying drawings, making a part of this specification, and to the letters of reference marked thereon.

To enable others skilled in the art to make and use my invention, I will proceed to describe the designs of the ornaments. —

A, represents an oval shaped heading on the sides along the four corners of the stove and along the lower sides.

B, the ornaments on the two doors - of a circular shape formed of three scallops or wavy lines representing leaves C, with raised corned shaped buttons D, on the centre of each leaf; At the sides are two leaves E, with eleven scallops - the two leaves E, are opposite to each other with a heavy scroll F, branching off on each side of the leaf E. The centre of the ornament is chequered in squares G, and surrounded with projecting leaves H. — The back of the stove is a single curved line I, with a circle owing J, in each of the four corners - and in the centre of this curved line I, is a second one K, corresponding with the outside line I.

What I claim as my invention and ornamental
